UNITED STATES PATENT OFFICE.

CONRAD ESPING, OF MOLINE, ILLINOIS, ASSIGNOR, BY MESNE ASSIGNMENTS, TO
MOLINE PLOW COMPANY, INCORPORATED, OF MOLINE, ILLINOIS, A CORPOR-
ATION OF VIRGINIA.

HAND LEVER.

Application filed November 4, 1919. Serial No. 335,725.

To all whom it may concern:

Be it known that I, CONRAD ESPING, a citizen of the United States, residing at Moline, in the county of Rock Island and State of Illinois, have invented certain new and useful Improvements in Hand Levers, of which the following is a specification, reference being had therein to the accompanying drawing.

10 The invention relates to hand levers.

Its general object is to provide an improved hand lever made of a minimum number of parts and in such a way that the cost of production will also be reduced to a minimum.

15 Other objects and advantages of the invention will appear from the specification and drawings.

In the accompanying drawings:

20 Fig. 1 is a perspective view of a hand lever embodying my invention.

Fig. 2 is a longitudinal sectional elevation of the same.

25 Fig. 3 is a side elevation showing the application of my improved lever to a harrow to actuate the harrow bars.

Referring to the drawings:

30 My improved lever comprises a lever bar 1, in the present instance in the form of a flat steel bar which is bent at its outer end laterally to form a lateral hand piece 2 having a hole 3 formed therethrough near its outer end. Adjacent the hand piece, the lever bar is formed with an outer longitudinal 35 guiding slot 4, and adjacent its inner end it is formed with a similar inner guiding slot 5. Extending along one side of the lever bar closely thereto so as to receive guiding support therefrom, is a latch rod 6 40 which is bent laterally at its outer end so as to form a lateral portion 7 which extends loosely through and is guided in the outer guiding slot 4 and at its inner end the rod is bent laterally to form an arm 8 which ex- 45 tends loosely through and is guided in the inner slot 5. This arm terminates in a locking latch 9 which is adapted to engage in the open slots 10 of a segment frame 11. The lateral portion 7 of the latch rod extends 50 along the inner side of the hand piece 2 of the lever bar in position to be grasped by the hand grasping the hand piece, and at its

outer end the lateral portion is bent so as to form a longitudinal extending terminal finger 12 which slides loosely through the hole 55 in the hand piece. The terminal finger 12 is formed at its inner portion with an annular shoulder 13 and the finger is surrounded by a coiled expansion spring 14 which bears at its inner end against said shoulder and at its outer end against the hand piece, the tendency of the spring in expanding being to thrust the latch rod inwardly and thereby engage its locking latch with the notches in the segment bar. 60

65 In the operation of the lever, the attendant grasps the hand piece 2 and includes in his grasp the lateral portion 7 of the latch rod, and in tightening his grasp, the latch rod will be drawn outwardly, thereby compressing the spring and withdrawing the locking latch from the notch in the segment frame with which it was engaged. The lever is then moved forwardly or backwardly to operate the connected parts, and when 70 the proper adjustment has been secured, the lateral portion 7 of the latch rod is released by the hand, and the spring in reacting will seat the locking latch in another notch in the segment bar. 80

75 The inner end of the lever may be variously formed and constructed to enable it to be properly mounted according to the particular type of mechanism with which it is to be employed. In the accompanying 85 drawings I have shown one application of the lever, namely, to operate the rocking tooth bars of a harrow. Referring to Fig. 3, a series of tooth bars 15 carrying harrow teeth are mounted to rock between end frame 90 bars 16, only one of which is shown, the several harrow bars having fixed thereto crank arms 17 to which is connected a reciprocating actuating rod 18. In applying my lever to a construction of this form, the lower end 95 of the lever bar is formed with a foot 19 which is bolted to the forward harrow bar, and the lever bar above the foot is pivoted as at 20 to the forward end of the reciprocating actuating bar 18, which bar is fastened at its forward end into a segment bar containing a number of notches to receive the locking latch of the lever. It will be manifest however that my invention is not 100

limited in its application to this particular use, as the novelty thereof resides in the specific form of the lever itself as above pointed out, and as specified in the claims, and this without regard to the particular type of mechanism or devices for which it is employed to operate.

From the foregoing construction, it will be noted that my improved lever comprises but three parts, namely, the lever bar, the latch rod mounted thereon, and the spring controlling the latch rod. As a result, the comparatively great number of parts characteristic of the prior construction above pointed out, are dispensed with, and the expense of production is consequently greatly lessened.

In the foregoing description and accompanying drawings, I have set forth my invention in the particular detailed form which I prefer to adopt and which in practice has been found to answer to a satisfactory degree the ends to be attained. It will be manifest, however, that these details may be variously changed and modified without departing from the spirit of my invention; and further, it will be understood that the invention is not limited to any particular form or construction of the parts, except in so far as such limitations are specified in the claims.

Having thus described my invention, what I claim is:

1. A hand lever comprising a lever bar having a laterally projecting hand piece provided with an opening therethrough, a latch rod having a lateral hand piece provided with a bent end insertable through the hole in the lever hand piece, and a spring surrounding the bent end of the latch rod serving to bias it to a latched position.

2. A hand lever comprising a lever bar formed of a single strip of metal one end of which is bent to form a lateral hand piece, a toothed sector formed of a single strip of metal, a latch rod formed of a single metal bar bent so as to provide at one end a handle portion cooperating with the hand piece of the lever bar and at the other end a latch portion formed to cooperate with the toothed sector, and a spring between the two handle portions serving to bias the latch rod to engaged position.

3. In a hand lever, the combination of a lever bar formed with inner and outer longitudinal guiding slots and having at its outer end a lateral hand piece, and a latch rod extending longitudinally along the side of the lever bar and formed at its outer end with lateral portion extending through and guided in the outer slot and disposed adjacent the hand piece in position to be grasped by the hand in grasping the hand piece, said latch rod being provided at its inner end with a lateral arm extending

through and guided in the inner slot and terminating in a locking latch.

4. In a hand lever, the combination of a lever bar provided with a lateral hand piece having a hole therethrough, a latch rod provided with a locking latch and mounted on the lever bar to move longitudinally thereof, said latch rod being formed with a lateral portion extending adjacent the hand piece in position to be grasped by the hand in grasping the hand piece, and said lateral portion having a terminal finger extending loosely through the hole in the hand piece, and a spring surrounding said terminal finger and acting respectively on the same and on the hand piece.

5. In a hand lever, the combination of a lever bar provided at one end with a laterally extending hand piece having a hole therethrough, a latch rod provided with a locking latch, said rod mounted on the lever bar to move longitudinally thereof and being formed with a lateral portion extending at the inner side of the hand piece in position to be grasped by the hand in grasping the hand piece, said lateral portion having a longitudinal terminal finger extending loosely through the hole in the hand piece and said finger being provided with a shoulder, and an expansion spring surrounding the terminal finger and bearing respectively against the inner side of the hand piece and against the shoulder.

6. In a hand lever, the combination of a lever bar provided at its outer end with a lateral hand piece having a hole therethrough and being provided adjacent said hand piece with a longitudinal guiding slot, said lever bar being provided with a second guiding slot adjacent its inner end, a latch rod extending longitudinally along the side of the bar and formed at its inner end with a lateral arm extending loosely through the inner guiding slot and terminating in a locking latch, and said latch rod being formed at its outer end with a lateral portion extending through the outer guiding slot of the lever bar and alongside the inner side of the hand piece in position to be grasped by the hand in grasping the hand piece, said lateral portion of the latch rod terminating in a longitudinal finger and extending loosely through the hole in the hand piece, and a spring surrounding said finger and bearing respectively against the same and the hand piece.

7. In a hand lever, the combination of a lever bar formed with outer and inner longitudinal guiding slots and bent laterally at its outer end to form a hand piece having a hole therethrough, a latch rod extending longitudinally along the side of the lever bar and bent laterally at its outer end in the form of a lateral portion extending through the outer guiding slot, said lateral portion

being in position to be grasped by the hand in grasping the hand piece, and said lateral portion being provided at its outer end with a longitudinal terminal finger extending 5 loosely through the hole in the hand piece, a spring surrounding the finger and bearing against the same and against the hand piece, and said latch rod being bent laterally at its inner end and extending through the inner guiding slot in the lever bar and terminating 10 in a locking latch.

In testimony whereof, I have affixed my signature hereto.

CONRAD ESPING.
